UNITED STATES PATENT OFFICE.

ISAIAH HUGHES, OF HOUTZDALE, PENNSYLVANIA.

TRAIN-STOPPING APPARATUS.

1,124,135.

Specification of Letters Patent.

Patented Jan. 5, 1915.

Application filed May 8, 1914. Serial No. 837,245.

To all whom it may concern:

Be it known that I, ISAIAH HUGHES, a citizen of the United States, residing at Houtzdale, in the county of Clearfield and State of Pennsylvania, have invented new and useful Improvements in Train-Stopping Apparatus, of which the following is a specification.

This invention relates to improvements in automatic train stopping apparatus and has particular application to fluid operated apparatus of this character.

In carrying out the present invention, it is my purpose to provide an automatic train stop which embodies in its construction, among other features, fluid motors disposed adjacent to the throttle valve and engineer's brake valve respectively and connected therewith and having connections with a source of fluid supply, and a valve located in said last named connection and having the stem thereof equipped with a wheel having a toothed periphery adapted to ride over a rack bar disposed along the track-way to open the valve whereby the motors will be placed in communication with the source of supply and the throttle valve closed and the engineer's brake valve operated to effect an application of the brakes to the wheels.

It is also my purpose to provide apparatus of the type set forth which will embrace the desired features of simplicity, efficiency and durability, which may be installed and maintained at a minimum expense and which will operate effectively under all conditions.

With the above and other objects in view, the invention consists in the construction, combination and arrangement of parts hereinafter set forth in and falling within the scope of the claims.

In the accompanying drawings; Figure 1 is a diagrammatic view of train stopping apparatus constructed in accordance with the present invention. Fig. 2 is a longitudinal sectional view through one of the fluid operated motors. Fig. 3 is an enlarged fragmentary elevation showing the connection between the particular motor and the throttle valve lever. Fig. 4 is an enlarged plan view of the valve controlling communication between the source of supply and the motors. Fig. 5 is an enlarged cross sectional view through the valve and operating rack therefor.

Referring now to the drawings in detail, 1 designates the throttle valve lever of a steam locomotive, while 2 indicates the engineer's brake valve located in the cab of the locomotive. Pivoted upon the throttle lever 1 is a bell crank lever 3 having one limb thereof connected through the medium of a pin and slot connection with the actuating rod of the latching dog and the opposite limb connected through a pin and slot connection with a link 4 slidably mounted upon the throttle lever 1 and slidably transversely thereof. Located in proximity to the throttle lever 1 and engineer's brake valve 2 are fluid motors *a* and *b* respectively, each comprising a cylinder 5 within which is mounted for sliding movement a piston 6 equipped with a piston rod 7 projecting outwardly of one end wall of the cylinder and connected with a cross head 8 slidably mounted within guides 9 connected with the adjacent head or end wall of the cylinder and projecting outwardly therefrom. Connected with the cross head 8 of the motor *a* is a rod 10 fastened to the link 4, while connecting the cross head 8 of the motor *b* with the handle of the engineer's brake valve is a rod 11.

In the present instance, each cylinder 5 is formed with exhaust ports 12, 12 at the opposite ends thereof so that the opposite ends of the piston will be in communication with the atmosphere whereby the engineer may manipulate the throttle valve lever and engineer's brake valve with ease and facility and without compressing air within the ends of the cylinders of the motor in the movement of the pistons within such cylinders. Leading into the cylinders 5 of the motors *a* and *b* at the forward ends of such cylinders, that is to say, the ends of the cylinders adjacent to the throttle lever and brake valve respectively, are branch pipes 13, 13 connected up with a common supply pipe 14 and the latter is connected with the main air reservoir of the air brake system of the train or the steam space of the boiler, as desired.

Located in the supply pipe 14 and disposed at an appropriate place upon the underframing of the locomotive adjacent to one line of rails of the trackway is a controlling valve 15 which, in this instance, is in the form of a globe valve. The stem of the valve is disposed in a horizontal plane and fixed to the outer end of the stem is a wheel

16 having the periphery thereof formed with teeth 17.

Arranged along the trackway at suitable intervals are rack bars 18 capable of movement to active and inactive positions and adapted, when in active position, to be engaged by the teeth 17 of the wheel 16 of a passing train whereby the valve 15 will be opened and fluid flow into the cylinders of the motors *a* and *b* thereby actuating the pistons within such cylinders. In the initial sliding movement of the piston in the cylinder of the motor *a*, a pull is exerted upon the link 4 thereby swinging the bell crank lever 15 with the effect to disengage the latching dog of the throttle lever from the quadrant and in the continued movement of such piston the throttle lever is swung to valve closing position, while in the sliding movement 20 of the piston 6 within the cylinder 5 of the motor *b* a pull is exerted upon the connecting rod 11 whereby the handle of the engineer's brake valve is swung from "full releasing" position or "running" position to 25 "emergency" position.

The rack bars 18 may be located at the entrances to the blocks, in the event of my improved apparatus being employed in conjunction with the block signaling system 30 and in such case each rack bar is connected up with the adjacent signal blade through suitable mechanism but when the blade goes to danger position the rack bar will be elevated or rendered active, while when the blade is in clear position the rack bar will be lowered or rendered inactive.

While I have herein shown and described one preferred form of my invention by way of illustration, I wish it to be understood 40 that I do not limit or confine myself to the precise details of construction herein described and delineated, as modification and variation may be made within the scope of the claims without departing from the spirit 45 of the invention.

Each rack bar 18 extends longitudinally of the trackway and is located adjacent to the outer side of one line of rails thereof. In the present instance, each rack bar is 50 slidably mounted upon guide rods 19 spaced apart in parallelism and lying in planes at right angles to the plane of the trackway. The outer ends of the rods 19, that is, the ends remote from the adjacent line of rails 55 of the trackway, are connected by means of a cross bar 20 and extending upwardly from the cross bar 20 is a pin 21 upon which is journaled a sheave 22 and trained over the sheave 22 is a cord 23 having one end thereof 60 passed through an eye formed in a block 24 upstanding from a cross bar 25 secured

to the guide rods 19 between the rack bar and the cross bar 20, the said end of the cord 23 being fastened to the rack bar 18. Interposed between the confronting faces of the 65 block 24 and rack bar 18 is a coiled expansion spring 26 encircling the cable or cord 23 and acting to slide the rack bar to active position and maintain the same in such position. The free end of the cord or cable 23 is 70 connected, through suitable mechanism, with the blade of the adjacent semaphore and when the blade goes to "clear" a pull is exerted upon the cord 23 thereby sliding the rack bar 18 to inactive position against the 75 action of the spring 26, while when the blade is actuated to danger position the cord or cable 23 is released and the spring 26 reacts to slide the rack bar to active position.

I claim:

1. In train stopping apparatus, a track instrument comprising a rack bar extending longitudinally of the trackway and capable of sliding movement to active and inactive positions, means acting normally to move the 85 rack bar to active position, and means for moving said rack bar to inactive position against the action of said first means.

2. In train stopping apparatus, a track instrument comprising a rack bar extending 90 longitudinally of the trackway and capable of sliding movement to active and inactive positions, a spring acting normally to move the rack bar to active position, and means for moving said rack bar to inactive position 95 against the action of said spring.

3. In train stopping apparatus, a track instrument comprising a rack bar extending longitudinally of the trackway and capable of sliding movement to active and inactive 100 positions, a spring acting normally to move the rack bar to active position, and signal operated means for moving said rack bar to inactive position against the action of said spring.

4. In train stopping apparatus, a track instrument comprising a rack bar arranged longitudinally of the trackway and capable of sliding movement to active and inactive positions, guide rods supporting said bar 110 and arranged at right angles to the trackway, means acting normally to move the rack bar to active position, and means for sliding said rack bar to inactive position against the action of said first means.

In testimony whereof I affix my signature in presence of two witnesses.

ISAIAH HUGHES.
